UNITED STATES PATENT OFFICE.

MICHAEL W. NEUENS, OF PORT WASHINGTON, WISCONSIN, ASSIGNOR OF ONE-HALF TO REINHARD STELLING, OF SAME PLACE.

WINDOW.

SPECIFICATION forming part of Letters Patent No. 634,019, dated October 3, 1899.

Application filed January 6, 1899. Serial No. 701,324. (No model.)

To all whom it may concern:

Be it known that I, MICHAEL W. NEUENS, a citizen of the United States, and a resident of Port Washington, in the county of Ozaukee and State of Wisconsin, have invented certain new and useful Improvements in Windows; and I do hereby declare that the following is a full, clear, and exact description thereof.

My invention has for its object to simplify and cheapen the construction of windows organized to permit of the sash being swung outfrom the frame without injury to the wood-work of either; and it consists in certain peculiarities of construction and combination of parts hereinafter set forth with reference to the accompanying drawings and subsequently claimed.

Figure 1 of the drawings represents an inside elevation of a window embodying my improvements having parts thereof broken away and in section; Fig. 2, a vertical transverse section of the window having its sash in normal position; Fig. 3, a similar view illustrating the lower sash swung out from the frame; Fig. 4, a horizontal section of said window, indicated by line 4 4 in the first figure, both sash being run down and the inner one swung out; Fig. 5, a detail elevation, partly in section and illustrating a removable portion of a parting-stop partly broken away to show a spring that bears upon the same; Fig. 6, a detail perspective view of a portion of a sash; Fig. 7, a detail sectional view of a portion of a sash and removable cord attachment; Fig. 8, a detail elevation of the parts shown in the preceding figure, and Fig. 9 a detail view illustrating the means for preventing loss of set-screws embodied in my improvements.

Referring by letter to the drawings, A B represent the stiles, C the head, and D the sill, of a window-frame that is of ordinary construction, except in matters of detail herein-after specified.

The vertically-adjustable sash E F in the frame is herein shown in connection with weight-cords; but various means may be employed for holding said sash in adjusted position.

The frame-stile A has a lower longitudinal recess containing a flat spring G, having its inner lower end made fast to said stile. Up-

per and lower castings H I are secured in the stile-recess by screws, and the holding-screw for the upper casting also serves as a pivot for a turn-plate J, the latter and said castings flush with the parting-rail on the stile, and this parting-rail has a removable section K, notched at its lower end to fit under an upwardly-extending lip of the lower casting, its upper end being also notched at its front to come under the turn-plate, the lower end of the permanent portion of said parting-rail being also notched to accommodate said turn-plate. At its rear the upper end of the removable parting-rail section is cut away to accommodate the free portion of spring G, and the latter operates by expansive tendency to tilt said parting-rail section out of the frame-stile recess when the turn-plate is swung far enough out of vertical position. Countersunk in frame-stile A are metal plates b, having tapped apertures for engagement of set-screws c, that also engage the inside sash-stop L, pertaining to said frame-stile, the screw-apertures in this sash-stop being of sufficient area to permit lateral adjustment of the same for the purpose of preventing rattle on the part of the sash. The thread portion of each screw-shank is of greater diameter than the remainder thereof, and arranged on the non-threaded portion of the shank, to oppose the inner side of the corresponding sash-stop L, is a spring-wire clip d, that prevents loss of said screw after its disengagement with a tapped frame-stile plate.

That portion M of the window-frame casing adjacent to the frame-stile A is provided with a notched outwardly-extending plate M' for the purpose hereinafter specified, and the removable section K of the parting-rail of said frame-stile is longer than the frame of either sash.

It is especially desirable when counter-weights are used with the sash E F that ends of the connecting-cords be readily removable from the sash-stiles that are normally adjacent to frame-stile A. Therefore the sash-end of each cord may be turned on a bolt e, that extends through an aperture in the head of a peripherally-notched annular shell N to engage with a clamp-nut f, and the ends of the spring-metal yoke g are extended through

other apertures in said shell-head and bent down against the turn of the cord under the bolt-head. The shell and its spring-yoke engage the usual cord-knot recess of a sash-stile, 5 and the expansive tendency of said yoke operates to hold the removable sash-cord attachment snug in place.

The stile B of the window-frame is provided with a detachable and adjustable stop L', held 10 in place by the same means as those described in connection with sash-stop L aforesaid, and the lower portion of sash-stop L' is recessed to engage the butts of a pair of hinges, each 15 of the latter having a leaf P thereof mortised in said frame-stile and held thereto by screws. Each hinge-leaf P is provided with a central recess, in which a flat spring h is secured to bear against the angularly-notched butt portion of a leaf Q, that has mortise engagement 20 with a longer leaf R, the latter being provided with an outer rib i, that flushes with the parting-rail S on stile B of the window-frame. Each of the hinge-leaves Q R is also provided with a dovetail rib j for the engagement 25 of a correspondingly-dovetailed vertical groove in a casting mortised in a sash-stile and made fast thereto.

The hinges are at suitable intervals one above another within a distance less than the 30 length of the sash-strokes. The upper hinge-engaging sash-stile castings T have their vertical grooves closed at the upper ends; but the vertical grooves of sash-stile castings T' are necessarily open at both ends to permit 35 adjustment of the sash in the window-frame. Above the closed upper ends of the grooves therein the castings T are apertured to correspond with the recesses formed in the sash-strokes for knots at the outer ends of cords that 40 connect with counterweights for the sash.

The leaves Q of the hinges swing out independent of the other leaves R, and the former leaves are for engagement with the castings mortised in a stile of the lower sash, the castings 45 mortised in a stile of the upper sash being engageable with said other leaves. However, it is practical to swing both leaves Q R of the hinges at the same time.

The hinge-leaves Q swing out against the 50 resistance of the springs h until their butt-notches clear the same, and these springs react to insure full return of the aforesaid leaves when the latter are swung into normal position.

55 To swing out the sash, the latter is adjusted to stand clear of the inside stop U on the frame-sill D, their stile-castings being engaged with the ribs j of hinge-leaves Q R, after which the inside sash-stop L is removed. 60 The lower sash is now free to be swung out, and if it be counterweighted the cord at the side farthest from the hinges is detached, the notched casing-plate M' serving as a catch for said cord. The lower sash having been swung 65 out, the parting-rail section K is detached from the adjacent frame-stile to permit swinging out of the upper sash, the counterweight-

cord farthest from the hinges of the latter sash being then detached and connected to the aforesaid notched casing-plate.

70 From the foregoing it is evident that either or both sash may be swung to stand at a right angle to the window-frame, and the counter-weight-cords, if any, being detached from the hinge-strokes of said sash the latter may be 75 readily removed should this operation be desirable.

Having now described my invention, what I claim as new, and desire to secure by Letters Patent, is—

80 1. The combination of a window-frame having a stile thereof provided with a lower longitudinal recess, upper and lower castings secured in the recess to flush with the parting-rail pertaining to the stile, a section of this 85 parting-rail having detachable engagement with said frame-stile recess and lower casting therein, and a turn-plate on the upper casting engageable with notched ends of the permanent and detachable parting-rail sections. 90

2. The combination of a window-frame having a stile thereof provided with a lower longitudinal recess, upper and lower castings secured in the recess to flush with the parting-rail pertaining to the stile, a section of the 95 parting-rail having detachable engagement with said frame-stile recess and lower casting therein, a turn-plate on the upper casting engageable with notched ends of the permanent and detachable parting-rail sections, and a 100 spring secured in the upper portion of the aforesaid recess to have expansive tendency against said detachable parting-rail section.

3. The combination of a window-frame having one stile thereof apertured and tapped 105 plates connected to both stiles of the frame, inside sash-stops provided with set-screws having enlarged threaded portions of their shanks engageable with said plates, and a spring-wire clip on the non-threaded shank 110 portion of each screw in opposition to the inner side of the sash-stop.

4. The combination of a window-frame having one stile thereof provided with a detachable section of parting-rail, inside sash-stops 115 having readily-detachable connection with both frame-strokes, hinges having leaves thereof in rigid connection with the frame-stile opposite the one having the detachable parting-rail section, each hinge having the swing portion thereof in the form of two vertically-ribbed leaves one of which closes within the other, and the window-sash having stiles thereof provided with longitudinally-grooved castings engageable with ribs of the aforesaid 120 hinge-leaves.

5. The combination of a window-frame having one stile thereof provided with a detachable section of parting-rail, inside sash-stops having readily-detachable connection with 125 both frame-strokes, hinges having leaves thereof in rigid connection with the frame-stile opposite the one having the detachable parting-rail section, each hinge having the swing

portion thereof in the form of two vertically-ribbed leaves one of which closes within the other and has its butt portion angularly notched; a flat spring seated in a recess of 5 the stationary leaf of each hinge to operate in conjunction with the angularly-notched leaf-butt, and the window-sash having stiles thereof provided with longitudinally-grooved castings engageable with ribs of the afore- 10 said swing-leaves of the hinges.

6. The combination of a window-frame having each stile thereof provided with a readily-detachable inside sash-stop, a parting-rail section in detachable connection with one 15 frame-stile, hinges having leaves thereof in permanent connection with the other frame-

stile, and other swing-leaves that close one within another, a guide-rib on each swing-leaf and a parting-rail rib on the larger of these swing-leaves; the window-sash, and 20 grooved castings fitted to sash-strokes for engagement with guide-ribs on the swing-leaves of the hinges.

In testimony that I claim the foregoing I have hereunto set my hand, at Port Wash- 25 ington, in the county of Ozaukee and State of Wisconsin, this 24th day of August, A. D. 1897, in the presence of two witnesses.
